UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,821.

Specification for Design.

Patented Jan. 5, 1915.

Application filed September 11, 1914. Serial No. 861,307. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design for corner piece for coffins and caskets comprises angularly arranged embossed surfaces having a central vertical protuberance 1 located at the angle of said faces and rising from a depressed background 2, the sides of the corner piece being formed with a plurality of relatively small lobes 3, one above the other and a relatively large lobe 4 beneath the parts 3, and terminating at the lower end of the corner piece.

The central figure includes an elongated ovoid convex protuberance 5 arranged with its larger end downward and terminating at the lower edge of the corner piece, a spherical boss 6 above the part 5, and a knob 7 above the part 6.

At opposite sides of the protuberance 5 the depressed surface 2 is formed with depressions 8 flaring outwardly toward their lower ends and terminating in the lobes 4.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
